OUTDOOR FLUORESCENT FIXTURE OR THE LIKE

Joseph H. Spaulding, South Fort Mitchell, Ky.

Application April 5, 1957, Serial No. 45,597

Term of patent 14 years

(Cl. D48—23)

Fig. 1 is a perspective view of an outdoor fluorescent fixture or the like, embodying my new design.

Fig. 2 is an elevational view thereof as seen from the opposite end of Fig. 1.

The end and top portion, not shown, are plain and the right half is the same as the left half shown.

The top portion of the fixture, not shown, is plain and the right half thereof is the same as the left half shown.

I claim:

The ornamental design for an outdoor fluorescent fixture or the like, as shown and described.
